United States Patent Office

Des. 192,688
Patented May 1, 1962

192,688

RETRIEVER FOR FISHING PLUGS, LURES, OR THE LIKE

Harold E. Watts, P.O. Box 1026, Florence, S.C.

Filed June 14, 1961, Ser. No. 65,595

Term of patent 14 years

(Cl. D31—4)

FIG.2

FIG.3

FIG. 1 is a front elevational view of a retriever for fishing plugs, lures, or the like, showing my new design;

FIG. 2 is a top plan view thereof; and

FIG. 3 is a side perspective view thereof shown in operating position.

I claim:

The ornamental design for a retriever for fishing plugs, lures, or the like, substantially as shown and described.
